UNITED STATES PATENT OFFICE.

HENRY FAWCETT, OF KIDDERMINSTER, ENGLAND, ASSIGNOR TO
J. & J. DOBSON, OF PHILADELPHIA, PENNSYLVANIA.

DESIGN FOR A CARPET.

SPECIFICATION forming part of Design No. 17,999, dated January 3, 1888.

Application filed September 22, 1887. Serial No. 250,000. Term of patent 7 years.

To all whom it may concern:

Be it known that I, HENRY FAWCETT, a subject of the Queen of Great Britain, and a resident of Kidderminster, England, have invented and produced a certain new and original Design for Carpets, of which the following is a full, clear, and exact description, reference being had to the accompanying drawing, forming a part of this specification.

10 My design is applicable more particularly to loop and cut pile carpets and to those woven with a border. It is illustrated in the drawing as composed of a center or body proper of floral design and a border of three parallel

15 rows, the inner row of floral design and of greater width than the outer rows, and a

fringe border of floral design and corner-pieces to correspond.

I claim—

1. The design for the center or body of the carpet, substantially as shown and described.
2. The design for the border pattern as a whole, substantially as shown and described.
3. The design for a bordered carpet, consisting of the center and border, substantially as shown and described.

In testimony whereof I have hereunto affixed my signature this 24th day of May, A. D. 1887.

HENRY FAWCETT.
